(57) **CLAIM**

I claim the ornamental design for a garden tool handle, as shown and described.

DESCRIPTION

FIG. 1 is a perspective view of the design of the present invention for a garden tool handle;

FIG. 2 is a right side elevation view of the invention of FIG. 1;

FIG. 3 is a front elevation view of the invention of FIG. 1;

FIG. 4 is a rear elevation view of the invention of FIG. 1;

FIG. 5 is a top end view of the invention of FIG. 1; and,

FIG. 6 is a bottom end view of the invention of FIG. 1. The broken lines represent portions of the article and form no part of the claimed design.
